UNIVERSAL JOINT.

1,109,006.

Specification of Letters Patent.

Patented Sept. 1, 1914.

Application filed March 21, 1910. Serial No. 550,661.

To all whom it may concern:

Be it known that I, ELMER E. NEAL, a citizen of the United States, residing at Bristol, county of Hartford, State of Connecticut, have invented a certain new and useful Universal Joint, of which the following is a full, clear, and exact description, such as will enable others skilled in the art to which it appertains to make and use the same, reference being had to the accompanying drawings, forming part of this specification.

My invention relates to universal joints, my object being to provide a structure which has firm driving connection between the coupling members but also permits great freedom of movement of one said member with respect to the other thereof, the parts being readily made and assembled.

To these ends, and also to improve generally upon devices of the character indicated, my invention consists in the various matters hereinafter described and claimed.

In the accompanying drawings, Figure 1 is a longitudinal sectional elevation; Fig. 2 is a fragmentary plan view, certain parts being broken away; Fig. 3 is a transverse sectional elevation; Fig. 4 is a perspective view of a slide and its coöperating socket plate, a portion of the slide being broken away; and Fig. 5 is a perspective view of one of the coupling members.

In the structure herein illustrated, the coupling member 1 is shown as having therethrough an opening 2 which is rectangular in cross section. Slidable longitudinally in said opening are oppositely disposed circular socket plates 3 each of which is rockable about its own center and has a curved socket 4 in its inner face. The outer faces of the said socket plates engage the inner walls of said coupling member 1, so that said coupling member 1 and said socket plates rotate together about the longitudinal axis of said coupling member. A second coupling member 5, here shown as a head integral with the shaft section X, has opposite ends 6 curved transversely and received in the said sockets 4 of the socket plates, the center of the curve of said head ends and of said sockets being in the longitudinal axis of the coupling. Thus, the socket plates 3 are rockable about their own centers to permit the head 5 and its con-

nected shaft to rock on one line, and said head is itself rockable in the socket plates on a line transverse to said first mentioned line of rocking. Furthermore, this structure permits the said head and its connected shaft to rock in any other line oblique to those already mentioned without cramping or binding, the socket plates rocking about their own centers and the head rocking in its sockets to permit this. Also, the coupling members 1 and 5 can slide freely longitudinally with respect to each other.

Preferably, a rib 7 upon each socket plate 3 enters a groove 8 in the adjacent end of the head 5, whereby the head and socket plates are held in the desired relationship with respect to each other and accidental displacement between said head and socket plates is prevented. As illustrated, the bottoms of the said grooves are curved parallel to the curvature of the ends of the head, and the outer faces of the ribs are correspondingly curved. Also, the socket plates, instead of merely bearing upon the walls of the coupling member 1 at the edges of said plates, are preferably supported upon slides 9, whereby each socket plate has a firm bearing in the slide. The said slides are rectangular and have substantially straight edges which slidably engage opposite walls of the coupling member 1, the outer faces of the sides lying against the adjacent walls of the coupling member, whereby easy sliding movement but firm driving connection exists between said coupling member and the slides. Each slide has a circular opening or socket 10 therethrough which receives the circular projecting portion 11 of its coöperating socket plate 3, the shouldered portion 12 of the socket plate lying against the inner face of the slide whereby the socket plates have ample bearing support in the slides and each slide is confined between a wall of the coupling member 1 and said shouldered portion 12 of its coöperating socket plate.

To assemble the joint it is only necessary to insert the socket plates in their slides, place these parts upon the ends of the head 5 and then slide the parts thus assembled into the coupling member 1.

In the structure shown the coupling member 1 has at one end a flange 13 for connection with a shaft section or the like Y, and

its other end is provided with a cap 14 having an enlarged opening 15 for the shaft section X.

Thus the present device comprises but few parts and these can be readily made and assembled, but at the same time there is firm driving connection between the parts and great freedom of movement of said parts with respect to each other, cramping and binding being obviated.

Having thus described my invention, what I claim as new and desire to secure by Letters Patent is:

1. The combination of a coupling member having a non-circular opening, oppositely disposed separate socket plates mounted in said opening, each plate being rockable upon an axis transverse to the plane of its body and each having a socket, members for so mounting said plates received in said opening, said members carrying said plates and having portions in contact along a substantial length with the sides of said opening intersecting said planes, and a second coupling member having oppositely extending projections received between said socket plates and in the sockets thereof, each of said projections being curved upon an axis transverse to the axis of rocking of said socket plates; substantially as described.

2. The combination of a coupling member having a non-circular opening, oppositely disposed separate socket plates slidably mounted in said opening, each plate being rockable upon an axis transverse to the plane of its body and each having a socket, members for so mounting said plates, said members being slidably received in said opening, carrying said plates, and having portions in contact along a substantial length with the sides of said opening intersecting said planes, and a second coupling member having oppositely extending projections received between said socket plates and in the sockets thereof, each of said projections being curved upon an axis transverse to the axis of rocking of said socket plates; substantially as described.

3. The combination of a coupling member, a slide in sliding and driving relation thereto, a socket plate rockably supported upon said slide to rock upon an axis transverse to the plane of said slide, a second coupling member received in the socket of

said socket plate and rockable therein on a line transverse to that of the rocking of said socket plate, and means for supporting said second coupling member in driving relation to said socket plate; substantially as described.

4. The combination of a coupling member, a slide in sliding and driving relation thereto and having a socket, a socket plate rockably supported in said socket of said slide, a second coupling member received in the socket of said socket plate and rockable therein in a line transverse to that of the rocking of said socket plate, and means for supporting said second coupling member in driving relation to said socket plate; substantially as described.

5. The combination of a coupling member, a slide in sliding and driving relation thereto and having a socket, a socket plate rockably supported in said socket of said slide and having a shouldered portion cooperating with said slide, a second coupling member received in the socket of said socket plate and rockable therein in a line transverse to that of the rocking of said socket plate, and means for supporting said second coupling member in driving relation to said socket plate; substantially as described.

6. The combination with a coupling member having a non-circular opening, of a slide slidable in said opening and having substantially straight edges along which it slides, whereby said slide and coupling member are in driving relation to each other, said slide having a socket therein, a socket plate having a shouldered portion engaging the face of said slide and also having a projecting portion rockably received in the said socket of said slide, a second coupling member received in the socket of said socket plate and rockable therein in a line transverse to that in which said socket plate rocks, means for preventing accidental displacement between said socket plate and said second coupling member, and means for supporting said second coupling member in driving relation to said socket plate; substantially as described.

In testimony whereof, I hereunto affix my signature, in the presence of two witnesses.

ELMER E. NEAL.
